ART OF REFINING HYDROCARBON OILS

Eugene C. Herthel, Flossmoor, Ill., assignor to
 Sinclair Refining Company, New York, N. Y.,
 a corporation of Maine

Application December 31, 1931
 Serial No. 584,069

2 Claims. (Cl. 196—147)

This invention relates to improvements in the manufacture of gasoline by cracking higher boiling hydrocarbon oils, such as gas oil, at temperatures exceeding 900° F. to produce cracked gasoline of high anti-knock value.

The severe cracking temperatures utilized to produce gasoline of high anti-knock value, temperatures exceeding 900° F. for example, tend to produce gasoline fractions including lower boiling constituents, lower boiling within the range of the gasoline fraction, in high concentration, the production of such low boiling gasoline constituents accompanying, within limits, the production of even lower boiling constituents incondensable at ordinary atmospheric temperatures and pressure. These severe cracking temperatures also tend to produce unstable hydrocarbon constituents which, although initially within the boiling range of gasoline, tend to polymerize to form higher boiling polymers, gums for example. Such gasolines require stabilization both physically and chemically.

This invention combines a physical stabilization and a chemical stabilization in a particularly advantageous manner to afford several advantages with respect to economy and simplicity. The physical stabilization is effected by fractionation under increased pressure, following fractionation under lower pressure to separate constituents higher boiling than suitable as components of the gasoline product, and the chemical stabilization is effected by digestion with an adsorptive catalyst, fuller's earth or similar clays for example, under elevated pressure, this elevated pressure being maintained through the fractionating operation, for physical stabilization, and the digesting operation, for chemical stabilization, the heat available from this fractionating operation being utilized in this digesting operation.

The invention will be further described in connection with the accompanying drawing, which illustrates, diagrammatically and conventionally, one form of apparatus adapted for the practice of the process of the invention as utilized in conjunction with one type of cracking system. It will be understood that other forms of apparatus may be used for practicing the invention and that the invention is useful in conjunction with other types of cracking systems.

Of the apparatus illustrated in the accompanying drawing, this invention relates more particularly to the operations carried out in the fractionating tower 1, the condenser 2, the receiver 3, the compressor 4, the condenser 5, the separa-

tor 6, the heat exchanger 7, the fractionating tower 8, the re-boiler 9 and the digester 10.

The apparatus illustrated in the accompanying drawing also includes a cracking heater 11 and an evaporator 12. In this particular cracking apparatus, raw oil is supplied through connection 13 to the mixing tank 14 by means of pump 15. The fraction comprising constituents higher boiling than suitable as components of the gasoline product separated in the fractionating tower 1, or part of this fraction, is supplied through connections 16 and 17 to the mixing tank 14 by means of pump 18. Part of this fraction may be discharged through connection 19. Part of this fraction may be introduced through connection 20 into the transfer connection 21 between the cracking heater discharge and the evaporator 12 by means of pump 22. The stock mixture from the tank 14 is forced through the cracking heater 11 into the evaporator 12 by means of pump 23, connections 24 and 25 connecting the mixing tank 14, the pump 23 and the cracking heater inlet. A pressure reducing valve 26 is provided in the cracking heater discharge for maintaining a substantial superatmospheric pressure in the cracking heater 11 and for effecting reduction of pressure between the cracking heater discharge and the evaporator 12. Tar is discharged from the lower part of the evaporator 12 through connection 27 and cooler 28. A refluxing medium, a part of the same raw stock supplied to the mixing tank 14 through connection 13 for example, may be supplied to the upper part of the evaporator 12 through connection 29, and the operation of the evaporator may be controlled by regulation of the rate at which the refluxing medium is so supplied. The mixture of vapors and gases separated in the evaporator 12 passes from the upper part of the evaporator 12 through connection 30 to the lower part of the fractionating tower 1. A reflux condenser 31 is provided for controlling the operation of the fractionating tower 1, control being afforded by regulation of the rate at which an appropriate cooling medium is circulated therethrough, by means of connections 32 and 33. The mixture of vapors and gases separated in the fractionating tower 1 passes from the fractionating tower 1 to the reflux condenser 31 through connection 35, condensate formed and separated in the reflux condenser 31 is returned, or refluxed, to the upper part of the fractionating tower 1 through connection 34, and the remaining mixture passes from the reflux condenser 31 to the condenser 2 through connection 36. Connection 37, discharging through

cooler 38, is provided for separating an intermediate fraction in the fractionating tower 1.

The following conditions are illustrative of operation of that part of the illustrated apparatus so far described in detail: Raw gas oil is supplied to the mix-tank 14 through connection 13. A temperature of approximately 280-290° F. and a pressure approximating 30-50 pounds per square inch is maintained at the upper end of the fractionating tower 1. A furnace oil fraction is discharged through connection 37 in amount corresponding approximately to 20-22% of the raw gas oil supplied through connection 13. A part of the condensed fraction separated in the fractionating tower 1 is pumped into the transfer connection 21 through connection 20 at a rate sufficient to maintain the temperature of the mixture entering the evaporator 12 through connection 21 in the neighborhood of 650-680° F., and the balance of this fraction is supplied to the mix-tank 14 through connections 16 and 17. The stock mixture from the mix-tank 14 is forced through the cracking heater 11 under pressure sufficient to maintain a pressure in the cracking heater discharge, in advance of the valve 26, approximating 400-600 pounds per square inch, and in the cracking heater 11 this stock mixture is heated to a maximum temperature approximating, for example, 925° F. The pressure on the hot oil products discharged from the cracking heater 11 is reduced as these hot oil products pass through the reducing valve 26, a pressure in the neighborhood of 35-60 pounds per square inch being maintained in the evaporator 12. The temperature in the upper end of the evaporator 12 is regulated to separate, in evaporator 12, a tar of chosen gravity, 5° A. P. I. for example. This temperature may approximate, for example, 600-625° F.

Constituents higher boiling than suitable as components of the gasoline product are separated in the fractionating tower 1. Constituents of the uncondensed vapors and gases separated in the receiver 3 suitable as components of the gasoline product are recovered as a condensate in the separator 6 and this condensate is combined with the condensate separated in the receiver 3. Constituents of this condensate mixture lower boiling than suitable as components of the gasoline product are separated in the fractionating tower 8. The fraction remaining, of controlled boiling range, is then subjected to digestion with an adsorptive catalyst under maintained pressure and at elevated temperature in the digester 10.

The uncondensed vapors and gases separated in the receiver 3 pass, by means of connections 39, 40 and 41, through the compressor 4 and the condenser 5 into the separator 6. Higher boiling constituents of this mixture of vapors and gases are thus condensed and the condensate is separated in the separator 6. The remaining gas mixture is discharged through connection 42. The condensate separated in the receiver 3 is forced, by means of pump 43, through the heat exchanger 7 and connection 44 into the fractionating tower 8. Condensate separated in the separator 6, discharged therefrom through connection 45, is combined with the condensate separated in the receiver 3 before the latter enters the heat exchanger 7. The condensate mixture introduced into the fractionating tower 8 through connection 44 is fractionated therein under a pressure substantially higher than that prevailing in the receiver 3, the heat required to effect the fractionation being supplied by means of the heat ex-

changer 7 and the re-boiler 9. A reflux condenser 46 is provided for controlling the operation of the fractionating tower 8, control being afforded by regulation of the rate at which an appropriate cooling medium is circulated therethrough, by means of connections 47 and 48. Condensate formed in the reflux condenser 46 is returned, or refluxed, to the upper part of the fractionating tower 8 through connection 49, uncondensed vapors and gases being discharged through connection 42. The condensate mixture separated in the lower part of the fractionating tower 8 passes, by means of connections 50 and 51, through the re-boiler 9 in which it is reheated, lower boiling constituents separated in the re-boiler being returned to the fractionating tower 8 through connection 52. This reheating is accomplished by circulating steam, or other appropriate heating medium, through the coil 53. From the re-boiler 9, the remaining condensate mixture is discharged to the digester 10, either through heater 54 and connection 51 or directly through connections 55 and 51. Pressure is maintained through the fractionating tower 8 and the digester 10 by means of valve 56 or valve 57 in the discharge connections from the digester 10. After passing through these valves or either of them the pressure on the condensate mixture may be reduced, for example, to a pressure approximating atmospheric pressure.

The following conditions are illustrative of operation of that part of the illustrated apparatus comprising the receiver 3, the separator 6, the fractionating tower 8 and the digester 10: Condensate is separated from the uncondensed vapors and gases in the receiver 3 under a pressure approximating 30-50 pounds per square inch, the temperature approximating 80° F. for example. A pressure approximating 250 pounds per square inch and a temperature approximating 80° F. are maintained in the separator 6 by means of the compressor 4 and the condenser 5. A temperature of approximately 110-120° F. and a pressure approximating 210-220 pounds per square inch are maintained at the upper end of the fractionating tower 8. The condensate mixture introduced through connection 44 is heated, by means of the heat exchanger 7, to a temperature approximating 270-280° F. as introduced. In the re-boiler 9 the condensate mixture is reheated to a temperature approximating 320-350° F. A temperature of approximately 400° F. and a pressure approximating 200-210 pounds per square inch are maintained in the digester 10.

Pressures upwards of about 200 pounds per square inch are with advantage maintained in the fractionating tower 8 and the digester 10. A temperature in the neighborhood of 400° F. is with advantage maintained in the digester 10 when using fuller's earth or similar clays as the adsorptive catalyst.

After passage through the digester 10, the gasoline product may be discharged directly through valve 56, connection 58 and cooler or condenser 59, or it may be given a supplementary treatment with an adsorptive catalyst at lower pressure in the treating tower 60. This supplementary treatment may be carried out with the heat available in the product discharged from the digester 10, or this product may be reheated in the heater 61 before entering the treating tower 60.

It will be understood that two or more digesters corresponding to digester 10 may be provided, with appropriate connections, to permit the use of one digester as an alternate for the other as

that other is being cleaned and recharged with fresh adsorptive catalyst. Similarly, two or more treating towers corresponding to tower 60 may be provided, with appropriate connections, to permit the use of one as an alternate for the other.

I claim:

1. In the manufacture of gasoline by cracking higher boiling hydrocarbon oils at temperatures exceeding 900° F. to produce cracked gasoline of high anti-knock value, the improvement which comprises fractionating a mixture of vapors and gases from the cracking operation proper to separate therefrom constituents higher boiling than suitable as components of the gasoline product, subjecting the remaining mixture of vapors and gases to condensation and separating a condensate including the gasoline product from uncondensed vapors and gases, increasing the pressure on the uncondensed vapors and gases and on this separated condensate, cooling the uncondensed vapors and gases and separating the resulting condensate, combining the two condensates and fractionating the condensate mixture under the increased pressure to separate therefrom constituents lower boiling than suitable as components of the gasoline product, digesting the remaining condensate with an adsorptive catalyst under maintained pressure and at a temperature not substantially lower than that at which it is discharged from the second-mentioned fractionating operation, and thereafter reducing the pressure on the digested condensate constituting the gasoline product.
2. In the manufacture of gasoline by cracking higher boiling hydrocarbon oils at temperatures exceeding 900° F. to produce cracked gasoline of high anti-knock value, the improvement which comprises fractionating a mixture of vapors and gases from the cracking operation proper to separate therefrom constituents higher boiling than suitable as components of the gasoline product, subjecting the remaining mixture of vapors and gases to condensation and separating a condensate including the gasoline product from uncondensed vapors and gases, increasing the pressure on the uncondensed vapors and gases and on this separated condensate, cooling the uncondensed vapors and gases and separating the resulting condensate, combining the two condensates and fractionating the condensate mixture under the increased pressure to separate therefrom constituents lower boiling than suitable as components of the gasoline product, digesting the remaining condensate mixture with an adsorptive catalyst under maintained pressure and at a temperature not substantially lower than that at which it is discharged from the second-mentioned fractionating operation, and thereafter reducing the pressure on the digested condensate mixture constituting the gasoline product.
